UNITED STATES PATENT OFFICE.

JACOB MULLEN THOMPSON, OF FOND DU LAC, WISCONSIN.

CONCRETE-WALL-MOLD DEVICE.

1,291,257.

Specification of Letters Patent.

Patented Jan. 14, 1919.

Application filed July 1, 1918. Serial No. 242,730.

To all whom it may concern:

Be it known that I, JACOB M. THOMPSON, a citizen of the United States, residing at 268 Superior St., Fond du Lac, in the county 5 of Fond du Lac and State of Wisconsin, have invented certain new and useful Improvements in Concrete Wall-Mold Devices; and I do declare the following to be a full, clear, and exact description of the invention, 10 such as will enable others skilled in the art to which it appertains to make and use the same.

This invention relates generally to molds, and more particularly to a device intended 15 to be used in connection with molds for forming concrete or cement walls and the like.

The principal object of the invention is to provide a clamp for holding the two 20 sides of a mold in their relatively spaced position, said clamps being easily manipulated and being capable of being placed at any point upon the sides of the mold.

Another object of the invention is to improve upon devices of this general class by 25 providing a device which will be extremely simple, strong, durable and inexpensive in construction, one which will be efficient and reliable in operation, and well adapted to 30 the purpose for which it is designed.

With these and numerous other objects in view, the invention consists of certain 35 novel features of construction and the combination and arrangement of parts as will be hereinafter fully described and claimed.

In the accompanying drawings forming 40 a part of the application, and in which similar reference characters designate like parts throughout the several views:—

Figure 1 is a cross sectional view through the wall and mold;

Fig. 2 is a detailed horizontal sectional view taken on the plane indicated by the line 2—2 of Fig. 1.

Fig. 3 is a longitudinal sectional view through one of the clamps; and

Fig. 4 is a perspective view of the same.

Referring more particularly to the drawings, the numerals 1 and 2 represent the two sides of the mold, each of these two sides being composed of one or more wooden planks 3, the latter extending longitudinally of the mold and being placed edge to edge as clearly shown by the drawings. These two 55 sides 1 and 2 are maintained in spaced parallel relation by means of two or more spac-

ing ties 4. These spacing ties 4 are flat metallic bars having openings 5 extending transversely between the sides 1 and 2 adjacent the side edges of the planks 3. Where 60 more than one plank 3 is used in one side of the mold the ends of the intermediate ties 4 overlap the meeting edges of the planks and hold both sets in their relatively spaced relation. 65

The reference numerals 6 designate flat metallic bars which extend through the sides of the mold between the side edges of the planks 3, and having their inner ends constructed into hook shape as at 7 to engage 70 the openings 5 in the spacing ties 4. The other ends of the bars 6 are connected to U-shaped metallic body members 8 by means of rivets 9. The ends of these U-shaped body members 8 are provided with screw- 75 threaded openings 10 through which operate screws 11. These screws 11 are headed at their outer ends as at 12, and are spiked at their inner ends as at 13, while they are provided intermediate of their ends with re- 80 duced portions 14.

The spikes 13 and reduced portions 14 of the screws 11 are swiveled in the ends of inverted U-shaped members 15 which serve as limiting the longitudinal movement of 85 the screws with respect to the base members 8.

The clamps at the top and the bottom of the mold are each provided with only one screw, while those used between the various 90 planks are each provided with two screws, one of which engages the lowermost plank and the other engages the uppermost plank.

The use and operation of the device will be readily understood without description 95 other than by stating that in constructing the mold the lowermost planks are first placed in their spaced parallel position with the spacing ties 4 disposed between them. The bars 6 are then engaged with the openings 100 in the ties 4 and the screws 11 are turned until their spiked ends are brought to bear against the outside of the planks. Other planks are then placed edge to edge upon the lower planks and the mold is built as high 105 as desired. After the concrete or cement is pried between the sides 1 and 2 and allowed to set, the screws are turned in the opposite direction so that the clamps may be removed and the planks taken down and used again 110 in making the wall still higher. The spacing ties 4 may be allowed to remain in the

wall as a reinforcement or else they may be withdrawn and used over and over again.

As various changes in form, proportion, and in the minor details of construction may be resorted to without departing from the spirit of this invention, it is to be understood that I do not wish to be limited to the construction herein shown and described other than as claimed.

10 I claim:

1. A device of the class described comprising a bar having one end formed with a hook adapted to be detachably connected to the spacing tie of a concrete wall mold, a body member secured to the other end of said bar and having a screw-threaded opening therein, a screw operating in said opening, and the means carried by said screw for limiting its forward and rearward movement with respect to said body member.

2. A device of the class described comprising a flat bar having one end formed with a hook adapted to be detachably connected to the spacing tie of a concrete wall mold, a U-shaped body member secured to the other end of said bar and having screw-threaded

openings in its two end portions, a screw operating in said openings, and means carried by said screw for limiting its forward and rearward movement with respect to the same.

3. A device of the class described comprising a flat bar having one end formed with a hook adapted to be detachably connected to the spacing tie of a concrete wall mold, a U-shaped body member secured to the other end of said bar and having screw-threaded openings in its two end portions, a screw-operating in said openings, and a U-shaped member having its end portions in swiveled connection with said screw and adapted to engage the end portions of the body member to limit the forward and rearward movement of the screw with respect to the same.

In testimony whereof I have hereunto set my hand in the presence of two subscribing witnesses.

JACOB MULLEN THOMPSON.
